INVENTOR

JOHN GIBBONS,

UNITED STATES PATENT OFFICE.

JOHN GIBBONS, OF WEST TROY, ASSIGNOR, BY DIRECT AND MESNE ASSIGNMENTS, OF THREE-FOURTHS TO STEPHEN J. BROWN, JOHN H. REYNOLDS, AND GEORGE E. WALDRON, ALL OF TROY, NEW YORK.

ROLLER-BEARING.

SPECIFICATION forming part of Letters Patent No. 487,699, dated December 6, 1892.

Application filed June 30, 1892. Serial No. 438,527. (No model.)

To all whom it may concern:

Be it known that I, JOHN GIBBONS, of West Troy, in the county of Albany and State of New York, have invented new and useful Improvements in Roller-Bearings, of which the following is a specification.

My invention relates to roller-bearings for journals of shafts and axles, but especially for journals of axles used for railway-cars; and the object of my invention is to provide a roller-bearing that will be efficient in operation and will be practically frictionless. I attain this object by the mechanism illustrated in the accompanying drawings, which, being herein referred to, form part of this specification.

In said drawings, Figure 1 is an end elevation of a journal-box containing my roller-bearing, with the axle shown in vertical section and the closure for said journal-box being removed to expose said roller-bearing. Fig. 2 is a horizontal section of said journal-box, showing a plan view of my roller-bearing and a portion of the axle. Fig. 3 is a transverse section of the journal-box, roller-bearing, and axle at the line X X on Fig. 2. Fig. 4 is a transverse section of the journal-box at the line Y Y on Fig. 2, the axle and roller-bearing being removed therefrom to show internal parts of said journal-box. Fig. 5 is a perspective view of one of the rollers of the roller-bearing shown in Fig. 2, and Fig. 6 is a plan view of a modified form of my roller-bearing.

As represented in the drawings, A designates the journal-box for a car-axle for rail-ways as adapted to receive my roller-bearing. Said journal-box is provided with a cylindrical chamber 1, having an inturned annular flange 2 at its inner end and an external circumferential flange 3 at the outer end of said journal-box. The annular flange 2 is provided with a circular groove 4 in its inner face, said groove being formed concentrically with the bore of said chamber, for a purpose hereinafter explained. The chamber 1 is preferably provided with a cylindrical lining 5, which is concentric thereto, and by which an enlarged circumferential groove 6 is formed at the inner end of said chamber for the purpose of giving suitable clearance for certain

revoluble parts that are arranged therein, as hereinafter explained.

B designates a detachable cap which forms a closure for the outer end of the journal-box A, to which said cap is secured by means of bolts 7. A cylindrical rim 8 is formed on the inner face of said cap for the purpose of bearing on the outer end of the cylindrical lining 5, so as to retain the latter in place. The inner diameter of said rim is greater than the bore of the lining 5, so as to give a suitable clearance for parts of the roller-bearing therein. The inner face of the cap B has a circular groove 9 formed therein to correspond to the groove 4, and it is made for a like purpose as the last-named groove. A chamber 10 is also formed in the inner face of said cap, said chamber being circular in form and having a concave seat 11 formed at its circumference.

C designates my roller-bearing, which, as shown in Fig. 2, has two series of rollers D of like form and provided with a long spindle 12 at one end and a shorter spindle 13 at the opposite end. The spindles 12 of one series are arranged to come between the adjacent rollers D of the other series, so that each end of the roller bearing the long spindles 12 and the short spindles 13 will alternate with each other, the ends of both sets of spindles at the same end of the roller-bearing being fitted to move on the same plane. All of the spindles at one end of the roller-bearing move in without touching the groove 4 and all the spindles 85 at the opposite end move in a like manner in the groove 9, and said grooves will retain all of said rollers in their allotted places whenever the journal-box A and its contained roller-bearing is removed as an entirety from a journal to which it is assigned, and thereby the operation of restoring said journal-box and roller-bearing to place will be greatly facilitated.

Each end of the rollers D is provided with 95 a circular projection 14 for the purpose of preventing said rollers from bearing upon each other at the conjoining ends and against the adjacent faces of the annular links by which the rollers are retained in position. In the 100 modification shown in Fig. 6 the roller-bearing C consists of two series of rollers of dif-

ferent forms. One of said series is composed of two rollers 15, having a spindle 16, which projects an equal distance from the outer end of said rollers, and a clear space is left between the adjacent ends of said rollers to receive the roller of the other series. The other series of rollers is composed of single rollers 17, adapted to enter the space between the adjacent ends of the rollers 15. Each roller 17 is provided with a spindle 18, which projects to an equal distance from each end of said roller. The length of the spindles 16 and 18 is the same, so that the ends of said spindles will be in the same plane.

15 E designates the annular links for retaining the several rollers in their required positions. The external diameter of said links is less than that of the rollers of the roller-bearing of either form shown, thereby relieving said links from any pressure against the journal or journal-box, the bore of said link being just sufficient to engage over the projecting ends of two adjacent spindles. Two series of said links are used at each end of the roller-bearing, and 25 they are so arranged that a ring of one series will bear on one side of one spindle and extend in one direction to engage with another spindle and a ring of the other series will bear against the opposite side of the spindle first 30 named in this paragraph and, extending in a direction opposite to that of the ring just referred to, engaging with another spindle. In this manner every spindle will have a different ring bearing against its opposite sides, 35 and the series of rollers will be bound together, so as to be irremovable by accident from their assigned places.

F designates a car-axle journal of the ordinary form with a concave seat 19, which, by 40 coacting with the similar seat 11 of the cap B, forms a suitable annular holder for a ball or balls 20 to produce an antifriction thrust-bearing for taking an endwise pressure on said car-axle.

45 What I claim as my invention, and desire to secure by Letters Patent, is—

1. In a roller-bearing, the combination of two series of rollers of like form arranged in reversed positions and each having a spindle 50 extending from its opposite ends, the length

of said extension at one end of said roller exceeding that of the other end, so that when the rollers of one of said series are reversed in respect to the other series the ends of the several spindles will move on the same plane, or 55 substantially so, as and for the purpose herein specified.

2. In a roller-bearing, the combination of two series of rollers so arranged that the rollers of one series will have a rotative movement 60 independently of the other series and each roller being provided with a spindle whose ends move on the same planes with the corresponding ends of the other spindles, and two series of annular links at each end of said spindles so arranged that each spindle will be engaged by different links at its opposite sides, 65 as and for the purpose herein specified.

3. In a roller-bearing, the combination of two series of rollers having a spindle projecting from the opposite ends of each roller and two series of annular links whose outer diameter is less than the diameter of said rollers, the latter being so arranged that the inner ends of the rollers of one series will overlap 70 the adjacent ends of the rollers of the other series, the spindles of each series of said rollers being arranged intermediately the bearing-surfaces of two adjacent rollers of the other series and said links being arranged so that 75 each spindle will be engaged by different links at its opposite sides, substantially as specified.

4. In a roller-bearing, the combination of a casing provided with an annular groove in its inner end, a cap for said box, having in its inner face an annular groove which corresponds to the groove of said box, two series of rollers provided with spindles which project from opposite ends of each roller, and two series of 80 annular links which are arranged so that two 85 different links will engage the opposite sides of each spindle, whereby the several rollers will be retained in their proper positions and the ends of spindles will be caused to travel 90 in said annular grooves, substantially as herein specified.

JOHN GIBBONS.
